(57) **CLAIM**

The ornamental design for a multi angle tile saw miter guide, as shown.

DESCRIPTION

FIG. 1 of the drawings is a perspective view showing the front, top, and right side of a multi angle tile saw miter guide embodying the design of my invention;

FIG. 2 is a top plan view of the miter guide;

FIG. 3 is a front elevation view;

FIG. 4 is a side elevation view of the right side;

FIG. 5 is a side elevation view of the left side;

FIG. 6 is a back elevation view;

FIG. 7 is a bottom plan view; and,

FIG. 8 is a top plan view similar to FIG. 2 with the usual environment of the miter guide that is not part of my design added in phantom lines, showing: the front of the miter guide abutting a vertical tile saw fence that is depicted by two horizontal phantom lines extending parallel to the front of the miter guide; the top of the miter guide supporting a piece of tile V cap that is depicted by horizontal phantom lines extending inclined to the tile saw fence; and a tile saw blade that is depicted by two horizontal phantom lines extending perpendicular to the tile saw fence in a position the blade occupies after making a miter cut in the piece of tile V cap.
